ANTIFLOODING FOUNTAIN PEN

Benjamin F. Miessner, Morristown, N. J.

Application June 7, 1951, Serial No. 230,377

11 Claims. (Cl. 120—48)

This invention relates to anti-flooding fountain pens and more particularly to improvements in this class of pens as disclosed in my co-pending patent application Serial No. 160,625, filed May 8, 1950, now abandoned.

In this application form there may be some objections raised to the method of filling the ink reservoir, since it cannot be filled in one stroke of the filler pump. After the first stroke, the barrel will be partially filled say to $\frac{1}{10}$, by the first filling operation of the pump, subsequent operations of the pump will eject this ink unless the point of the pen be held upright, and even then some of the ink in the collector will be ejected before the air in the barrel flows out. This results in ink running down the barrel and onto the operator's fingers, both from the ejected ink and from that adhering to the pen end of the barrel after submersion in the ink supply vessel.

Such pens can be filled by removing the barrel from the pen end and pouring ink into it from a bottle, or by introducing it with a medicine dropper, but this may be objectionable or inconvenient and messy. The object of this present invention therefore, is to allow filling of the pen barrel, through the point end, to keep the ink and air in the barrel sealed therein until its ejection into the collector is desired, and then only in measured amounts.

The pen of my present case may employ a rigid barrel of any desired material, transparent or opaque. It is fitted with any suitable type of top end pump, such for example as that disclosed in Figure 2 of the above-mentioned co-pending application. In the present case the pen end contains a collector, somewhat similar to the radial fin type shown in Figure 2 of my application Serial No. 206,678, filed January 18, 1951, now Patent Number 2,642,041, and with a similar pen point, hood and nipple, and an axial hole through which air and ink passes in filling the pen and which acts as an air breather hole for the ink collector assembly.

In the present case the form of construction utilizes a sleeve type of valve which is utilized in three different arrangements wherein one form is shown in Figures 1 to 6 inclusive, the second form in Figures 7 to 9 inclusive and the third form shown in Figures 10 to 12 inclusive. In the first form,

Figure 1 is a longitudinal sectional view through the completed pen;

Figure 2 is a view similar to Figure 1 but with the moving or pump parts in a different position than shown in Figure 1;

Figure 3 is a view on the line 3—3 of Figure 1;

Figure 4 is a view on the line 4—4 of Figure 1;

Figure 5 is a view on the line 5—5 of Figure 1;

Figure 6 is a plan view of the collector showing the slit for feeding ink to the fin area of the collector; In the second form,

Figure 7 is a sectional view through the upper part of the pen, the lower part of which is shown in Figure 7a;

Figure 7a is a sectional view through the lower part of the pen, the top part of which is shown in Figure 7;

Figure 8 is a view on the line 8—8 of Figure 7a;

Figure 9 is a view on the line 9—9 of Figure 7a;

In the 3rd form,

Figure 10 is mostly a sectional view through the pen, the hood end of which is broken off since it is like the end shown in Figure 7a;

Figure 11 is a view on the line 11—11 of Figure 10;

Figure 12 is a view on the line 12—12 of Figure 10.

In the different views wherein like numbers refer

to corresponding parts and referring to the first form, 1 is a hood attached to a connector 2 by screw threads 3. To the other end of the connector is a barrel 4 which is preferably cemented to the connector 2 against the collar 5 of the connector. It is to be noted that the hood 1 also engages the collar 5.

At the upper or top end of the barrel 4 is a plug 6 which acts to hold a pump sac 7 securely within the top of the barrel, cement being preferably used to make an ink tight joint. Carried within the plug 6 is an operating rod 8 having a knob 9 and carrying a spring 10 between the knob 9 and a pin 11 which is fastened to the rod 8. The pin 11 and one end of the spring 10 are seated in a recess 12 at the end of the plug 6 which has a longitudinally extending recess or groove 13 to allow the pin 11 to travel back and forth as the rod 8 is operating which is later to be described.

The inner end of the pump sac 7 is curved back and anchored at 14 to the rod 8 as by cementing. Also attached to the rod 8 as by screw threads 15 is a rigid pump tube 16 preferably of suitable metal the opposite end of which is positioned in a sealing member 17 that is cemented to the inner wall of the barrel 4 and also to the upper end of the connector 2 and to the upper end of the collector 18. The end of the pump tube 16 that is normally shown in the sealing member 17 has a plug 19 securely fastened in this end of the pump tube. The pump tube has a lateral hole 20 therein located closely adjacent to the sealing member 17 when the pump tube is in its normal position as shown in Figure 1. The pump tube also has another hole 21 therein located closely adjacent the end of the rod 8. The function of these holes will be presently described. The hood 1 has a bore 22 large enough to leave an annular space around the shank 23 of the pen point. The shank 23 is located in a recess or bore in the end of the collector 18, which has a smaller bore to receive a breather and filler tube 24. The collector 18 also has a hole 25 in alignment with the hole through a stationary breather and filler tube 24 and this hole 25 extends into a recess 26 in the collector and into which the end of the pump tube 16 projects when the pump rod is pushed downwardly as shown in Figure 2.

It is to be noted that the collector 18 has fin areas 27 within the hood for receiving ink coming from the recess 26 by way of the slit 28 as shown in Figure 6.

In the operation of the form shown in Figures 1-6 inclusive, it is to be noted that when the parts are in the position shown in Figure 1 the plug end of the pump tube 16 normally seals the ink reservoir in the barrel 4 from the collector 18. However, when pressure is applied to the knob 9 the pump tube 16 is pushed through the rubber disc or sealing member 17.

If the pen is empty of ink and the pump rod be turned so that the pin 11 is aligned with its guide slot 13 and the pump rod 8 depressed, the pump sac member 7 will compress the air in the pen barrel 4. The air pressure in the barrel will rise until the lateral hole 20 in the pump tube 16 is passed through the sleeve valve 17 and the barrel will then be connected through the recess 26 in the collector by way of the hole 21 in the tube 16. The compressed air in the barrel will then expand out of the same through the hole 21, tube 16 and hole 20 into the clearance hole or recess 26 and slit 28 in the collector. It will be noted that the depth of the recess 26 is such as to allow sufficient movement of the pump tube 16 for the full length of the stroke of the pump rod 8. The action just described allows the air to pass through the axial hole 25 and the hole in a stationary breather and filler tube 24 to the external atmosphere. If the pen point has been immersed in ink in a bottle or some container, this air will bubble up to free atmosphere. When the pump rod 8 is released the spring 10 acts to return the pump member back to the position shown in Figure 1. This reduces the air pressure in the barrel reservoir so that atmospheric pressure on the surface of the ink in the supply vessel will move ink into the barrel reservoir, by way of the axial hole in the feed bar, the clearance hole or recess 26, the upper end of the collector, through the lateral hole 20 through the pump tube 16 and out of the hole 21 in the upper end of the pump tube whence it

drops by gravity into the barrel. This movement of the ink into the pen continues until the hole 20 in the pump tube has passed back into the bore of the rubber sleeve valve or sealing member 17. This pump rod compression and release will pump about 1 cc. of ink into the barrel and this operation is repeated until the ink in the barrel has reached up to or over the hole 21 in the pump tube 16. Any further pump depressions will only serve, with the pen point down, to expel any excess ink in the barrel above the hole 21 when the hole 20 is still on the collector side of the sleeve valve or sealing member 17.

During this filling operation the ink collector 18 will have become filled with ink which feeds down by gravity and capillary attraction into the longitudinal slit 28 and into the radial capillary spaces or fin area 27 as well as through the annular ink space inside the pen and to the outside of the pen bore 22, through the hole 29.

The filled collector contains sufficient ink to write several pages and when the collector ink level drops down towards the point end air flows into its upper end through the axial hole in the stationary breather and filler tube 24 and collector 18 to replace the used ink so that air cannot increase or decrease in pressure with respect to external atmospheric pressure due either to temperature variations or to external barometric pressure variations. The ink thus feeds out of the collector to the pen point by gravity and capillary action. The collector 18 has sufficient capillary force to retain its ink against the downward flow of gravity, but will allow the ink to flow to the writing point freely, but with no tendency to overflow.

When the initial supply of ink in the collector, resulting from a barrel filling operation as described, is used up the collector may be refilled from the barrel by turning the pen point up so that the hole 21 in the pump tube 16 is submerged in ink within the barrel and then operating the rod 8 and tube 16 as in the barrel filling operation. One or more movements of the said rod and tube will refill the collector with ink as described more in detail with respect to Figure 7.

From what has been said concerning this form of my invention it will be seen that the pen has its main reservoir ink normally sealed therein and it cannot escape into the collector by temperature or atmospheric pressure variations. Furthermore, this pen construction cannot leak or flood hence the objections of conventional pens are overcome, as well as the objections which I have personally found in my experience with many types of pens.

In the form shown in Figure 7 the free end of the barrel 4 is closed with a slightly different plug 30 from plug 6. In this form a spring 31 is located within the recess 32, within the plug 30 that is anchored as by cementing to the barrel 4. Plug 30 has a reduced end 33 which serves to clamp the flexible rubber pump member 34 securely within the end of the barrel. Also carried by the plug 30 is a rod 35 having a cooperating knob 36 fastened thereto or integral therewith. To the inner end of the rod 35 is fastened a pump tube 37 of suitable material which may be of suitable metal such as shown in Figure 1 or of strong plastic material. The upper end of the pump tube 37 has threads thereon to receive a lock cap 38 which forces the inner end 39 of the pump member 34 into strong locking engagement with cement to the pump rod 35, the pump tube 37 being screwed into the inner end of the rod 35.

In this construction the lower end of the pump tube 37 passes through a plug member 40 of suitable material such as rubber that is cemented along with a force fit to the interior wall of the barrel 4. In this form the collector 41 is somewhat different from the collector 18 of Figure 1 in that it has a recess at its inner end to receive a rubber tube 42 that is cemented into a recess in the collector. Positioned in the bottom of the tube 42 is a relatively soft rubber disc 43 against which the end of the pump tube 37 is normally positioned thereby sealing the tube 37 at its interior end. Along the outer wall of the collector is the slit 28" that connects a space 45 with the space 46 adjacent the fin area of the collector, this fin area having access to the space 47 that opens into an annular space 48 around the shank of the pen as well as to the annular bore 22 around the pen. In this form of my invention when the rod 35 is pulled outwardly against the spring 31, the inner end of the pump tube 37 is pulled away from the disc 43 and out of rubber sleeve

42 so that the open end of the pump tube will allow air or ink to move into the space 45 and through the connecting space 46 via slit 28" from the pen point. It may be noted in passing that the longitudinal hole in the pump tube 37 is about .050ths of an inch which I have found to give satisfactory operation.

To fill the pen reservoir barrel the pump knob 36 is pulled out and released a couple of times, with the point end of the pen immersed in ink in a container. As 10 the knob is pulled out the volumetric space occupied by the pump in the barrel decreases, thus reducing the internal air pressure in the barrel. This continues until the free end of the pump tube 37 emerges from its encircling rubber tube 42, at the end of this outward pump stroke. Ink then flows into the barrel by way of the axial bores in the breather and filler tube and collector, the lateral hole in the collector, the longitudinal slot 28" in the collector inside the connector, to the space 45 between the end of the connector and the barrel plug 40 15 and then through the now openly exposed end of the pump tube 37, through this pump tube out of its upper lateral hole 21" the same as in Figure 1 and then falls by gravity to the pen end of the reservoir. With release of the pump rod 35 the spring 31 forces the pump sac 20 to expand in volume, thus compressing the air in the barrel. Air then flows out of the barrel through the lateral hole 21" in the upper end of the pump tube and down through this tube and out of its free end and into the space 45. Thence down along the longitudinal slot 25 28" and out through the axial bores in the collector and feed bar, whence it bubbles up through the ink in the container to free atmosphere. This outward flow of air continues until the end of the pump tube enters the inner rubber tube 42 after which the tube end is sealed as heretofore explained. If the pump knob 36 is again pulled out, it will again decrease the pressure of air in the barrel and, as soon as the pump tube emerges from its inner rubber tube closure, the pump will again draw ink into the reservoir as before.

40 These pumping operations are thus continued until the air in the reservoir has been replaced by ink up to the level of the lateral hole 21" in the pump tube. Should the ink level rise above the level of this lateral hole, the excess ink will be forced out of the barrel through this hole, the pump tube and into the collector and ink container, when the pump knob is released, and until the end of this tube is again sealed by entering the rubber inner tube 42 which acts with the member 43 as a valve. In this filling operation, the ink collection spaces in the 45 radial fin section of the collector and the annular spaces around the pen point will become saturated with ink leaving the larger non-capillary axial hole and longitudinal slot free of ink and filled with air. The collector spaces will hold sufficient ink for several pages of writing, and as this is written out, air flows upwardly into these ink spaces from free atmosphere through the axial hole at the outer end of a stationary breather and filler tube 24, the lateral space 46 and longitudinal slot in the collector, upwardly and downwardly along the collector. 50 With this construction there is no trapped air above the ink in the collector and annular spaces, which feed ink to the point, and the air pressure there is always equal to outside atmospheric pressure, irrespective of its temperature variations or variations of external barometric pressure. When the ink in the collector has been written out, the collector may be refilled from the barrel reservoir by turning the pen, point up so that the lateral hole 55 21 in the pump tube is submerged in ink in the barrel and then pulling out and releasing the pump knob. Pulling out the knob draws air into the barrel through the pump tube and this bubbles out of the lateral pump tube hole 21" through the ink to the now upper pen point end of the barrel ink reservoir. Release of the pump knob then expands the pump, compresses the air in the barrel and forces ink through the lateral pump tube hole 21", through this tube up into the collector. One or more such operations will refill the collector with ink after which the barrel then again is sealed from the 60 collector by the normal position of the pump tube 37 forced thereby by the pump spring 31.

If desired the outward stroke of the pump may be made long enough to carry the free end of the pump tube just beyond the barrel side of the rubber plug. In this case the collector can be refilled also with the 65 point end of the pen down, since ink will flow directly

through the plug hole for a short fraction of the return pump stroke, following which the ink in the pump tube will be discharged also, after which air from the barrel will flow, through the lateral hole in the pump tube, until the free end of the pump tube enters its sealing tube valve. Thus the amount of ink discharged is limited for each such operation.

In the third form of my invention shown in Figures 10-12 the hood end is the same as in Figure 7a and the barrel 4 is of suitable stiff material and the plug 49 at the upper end of the barrel is force fitted and cemented to the barrel 4, while the spring 50 is mounted wholly within the barrel and acts against the inner end of the plug 49 and a bushing 51 that fits ink tight in the plug 49. In this form the air tube 37' is substantially the same as in Figure 7 except the hole 21" is located closely adjacent the collar 52 that is fastened to the pump tube rod 37. Within the barrel and fastened to the pump tube 37' as by a pair of lock nuts 53 is a piston 54 having ring members 55 for the usual purpose. In this form as the pump tube is pulled outwardly, air will be compressed in the barrel 4 and be forced out through hole 21" and pump tube 37'. On releasing the knob 36, the spring 50 will force the piston 54 and pump tube 37' toward the pen end of the device, thus drawing ink into the barrel through the pump tube 37' and its lateral hole 21", so each outward pull of the pump knob 36 will force air out of the barrel and the return spring force stroke will draw ink into it in the filling operation.

In refilling the empty collector as stated, the pen is held point up with the lateral hole 21" submerged in ink and the top knob 36' is pulled outwardly until the collector is filled, or with one or more fractional outward pump knob strokes until the collector is filled as observed in the open end of the upwardly turned hood and pen. The alternate modifications of design as shown and described, obviously employ the same general principles in each case namely, that the pens are easily filled by a series of pumping operations, that the ink in the reservoir is normally sealed therein and cannot be forced out by temperature or barometric pressure variations, and that it can, when desired for refilling the collector, easily be ejected in small amounts by subsequent pump operations, into the collector which itself has sufficient capillary force to hold its ink against gravity, and which has an air pressure equalizing connection to external atmosphere, so that its ink feed to the pen point is not disturbed by trapped air pressure irregularities, and flows only by capillary and gravity action to the pen point nibs.

Additionally, as disclosed, these modified designs permit use of the pump whose operating end is normally spring biased against the upper end of the pen, safe from any accidental operation.

Having thus described my invention, I claim:

1. A fountain pen having a hood and a barrel joined by a connector, a collector having a hollow end and also having a passageway communicating therewith fitting tightly into the connector and preferably terminating tightly into the connector, the opposite end of the collector being located within the hood and provided at its extremity with a bore, a stationary breather and filler tube located in said bore, said collector having a larger bore concentrically located with respect to the first mentioned bore, a pen having its shank located in said larger bore, said larger bore terminating in said passageway, this opposite end of the collector having its outer surface provided with closely spaced fins having a longitudinal ink feed slit crossing the fins and assisting in feeding ink to the fins and to the pen point, a sealing member securely fastened to the inner wall of the barrel as well as to the end of the connector and hollow end of the collector, a plug securely located in the outer end of the barrel, a pump rod reciprocally carried by said plug, a pump tube operatively connected at one end to said rod with its other end plugged up thereby normally preventing access of ink from the barrel to the collector and this plugged end being slidably located in said sealing member, said pump tube having a lateral hole therein just above the plugged portion therein, said pump tube also having a lateral hole adjacent the inner end of said pump rod and a flexible pumping member operatively connected between the pump rod and the end portion of the barrel for the purpose described.

2. A fountain pen as set forth in claim 1 further defined in that the hollow portion of the collector is sufficient in length to allow the lateral hole in the pump tube to pass through said sealing member into said hollow portion when the pump rod is given an operative stroke.

3. A fountain pen as set forth in claim 1 further defined in that the plug in the end of the barrel has a longitudinal groove therein and the pump rod a pin located so the rod is normally held in inoperative position by the plug, the pin being slideable in said plug groove when the rod is arcuately turned to bring the pin into alignment with the groove.

4. A fountain pen having a hood and barrel connected to opposite sides of an annular shoulder on a connector, a collector having a portion extending through the greater part of the hood and having a centrally located hole therethrough and fins on the exterior surface with a longitudinal slit through the fins and having access to ink when it comes from the barrel, said collector having another portion of reduced diameter extending through the length of said connector and having a hole therethrough, said hole being in communication with said centrally located hole and having a diameter and length to accommodate the movement of a pump tube, the collector end toward the pen having a recess to receive the pen shank and another recess to receive a breather and filler tube having a hole therethrough in alignment with the said hole going through the collector, a sealing member over the ends of the collector and connector within the barrel and having a hole therein in alignment with the hole in that portion of the collector of reduced diameter, a plug in the free end of the barrel and having a guide slot therein, a pump rod slidably carried by said plug and having a pin located to hold the pump rod normally in inoperative position but arranged to move into said slot on turning the rod, a pump tube fastened to said rod and extending into said sealing member, this end of the pump tube being plugged for a distance about the thickness of the sealing member, also this end of the pump tube having a lateral hole located adjacent the plug, said pump tube having another lateral hole near the end of the pump rod, said holes in the pump tube acting to control the flow of ink from the barrel to the collector and a flexible compression member cooperatively connected to the pump rod and the plug end of the barrel.

5. A fountain pen as set forth in claim 4 further defined in that the portion of the collector within the connector has a uniform diameter through its length while the portion having the fins has a tapering diameter from the connector toward the pen point where it is the smallest.

6. A fountain pen as set forth in claim 4 further defined in that a spring is associated with the pump rod to return it to normal starting position.

7. A fountain pen having a hood carrying a pen having the usual nibs and circular shank and a barrel fastened to opposite ends of a connector, and a collector having a fin covered portion located within the hood and another portion located within the connector, the fin covered portion having a centrally located hole therethrough with a breather and filler tube extending from the pen nibs into said hole, the collector having a longitudinal slit to pass ink from said centrally located hole onto said fins, means for passing ink from the barrel to the collector, said means including a sealing member cemented to the inner wall of the barrel and also to the inner ends of the collector and connector, a pump rod, having a pump tube attached thereto and extending through said sealing member, this extending end being closed by suitable blocking means and this end being normally slidably located in said sealing member, the pump tube having a lateral hole normally close to said sealing member and another lateral hole in the pump tube close to the end of the pump rod and a flexible compressing member co-operatively connected to the pump rod and the free barrel end for moving the pump rod and pump tube to bring the pump tube to a position where the lateral hole in the pump tube normally adjacent the sealing member is moved below the sealing member and the other lateral hole freely located in the ink reservoir for the purposes described.

8. A fountain pen as set forth in claim 7 further defined in that a spring is operatively associated with the

pump rod to insure its return to normal starting position and further defined in that means are provided for insuring that the rod cannot be accidentally operated.

9. A fountain pen having a hood carrying a pen having the usual nibs and circular shank and a barrel fastened to opposite ends of a connector and a collector having a fin covered portion located within the hood and another portion located within the connector, the collector having a bore concentric with the pen shank to receive the inner end of said pen shank, the hood having a bore at its free end to receive the shank of the pen adjacent the pen nibs, the hood bore being large enough to leave an annular space around the pen point and at least a part of the shank, a hollow breather and filler tube extending from the outer surface of the hood free end through the shank of the pen into said bore in the collector, the collector having an axial hole in alignment with the hollow part of the breather and filler tube, means for passing air and ink from the barrel to the collector, said means including a pressure actuating device and a hand and spring operated pump rod operatively connected to said device together with a pump tube fastened to said pump rod and extending axially through the barrel into part of the collector and having a lateral hole in the tube located near the union of the rod and tube for passing air and ink from and to the barrel, said pump tube at its inner end being normally closed by suitable blocking means, the pump rod and pump tube being movable to air and ink discharge positions to render said blocking means inert and co-operative means including fins on the collector and at least one intercepting passageway along the length of the connector across the fins for passing air and ink from said tube and barrel through said passageway and fins of the collector when said pump rod and pump tube are in discharge position.

10. A fountain pen as set forth in claim 9 further defined in that the pump tube extends from the pump rod into a part of the collector and against said blocking means where it is normally held by said spring and from which it is released by an outward pull on said rod.

11. A fountain pen including a hood and barrel with a connector for coupling them together, a pen point hav-

ing its shank extending into the hood, an ink collector having an axial bore therethrough and also having one end extending into the hood and the other end into the barrel area, a sealing member having only a single central hole therein and fitting tightly within the barrel wall and located directly over the inner ends of said collector and connector, at least the end of the collector that extends into the hood having radially projecting circular fins thereon extending from a point closely adjacent the hood end of the connector to a point near the shank of the pen point, the collector having a single side slit extending longitudinally of its full length to at least bring ink to the fins, means for passing air and ink through the collector, said means comprising a pumping device having a pump rod with a compressing member operatively connected therewith at the free end of the barrel, a pump tube attached to the inner end of the pump rod and extending within the barrel thru the single hole of the sealing member and cooperative means associated with the inner portions of said pump tube and said sealing member brought into operation only by longitudinal movement by said pump tube for controlling the movement of air and ink to the barrel and pen point when the pump rod is operated, said operation being by hand in one direction and by said compressing member in the opposite direction.
